(57) **CLAIM**

The ornamental design for a lighting element, as shown and described.

DESCRIPTION

FIG. 1 is a front view of a lighting element;

FIG. 2 is a top view thereof;

FIG. 3 is a right-side view thereof, the left-side view and the rear view being mirror images of the right-side view;

FIG. 4 is a bottom view thereof;

FIG. 5 is a perspective view thereof; and,

FIG. 6 is a cross-sectional view thereof taken along lines 6-6 in FIG. 2.

Only the portions with the dark surface shading form part of the claimed design.

The dot-chain lines illustrate a boundary between claimed and unclaimed surfaces and form no part of the claimed design.

The broken lines depict portions of the lighting element and form no part of the claimed design.
